UNITED STATES PATENT OFFICE.

WILLIAM E. GREER, OF AKRON, OHIO, ASSIGNOR TO THE AKRON STANDARD MOLD COMPANY, OF AKRON, OHIO, A CORPORATION OF OHIO.

DESIGN FOR A TIRE.

Application filed March 8, 1927. Serial No. 21,050. Term of patent 14 years.

To all whom it may concern:

Be it known that I, WILLIAM E. GREER, a citizen of the United States, residing at Akron, in the county of Summit and State of Ohio, have invented a new, original, and ornamental Design for a Tire, of which the following is a specification, reference being had to the accompanying drawings, forming a part thereof.

In the drawings:

Figure 1 is a plan view looking upon a section of a tire showing my new design; and

Figure 2 is a fragmentary cross-section on the line 2—2 of Figure 1.

I claim:

The ornamental design for a tire, as shown.

WILLIAM E. GREER.
